UNITED STATES PATENT OFFICE.

JACOB J. KLEIN, OF KEARNEY, NEBRASKA.

CLOSET.

1,096,843.

Specification of Letters Patent. Patented May 19, 1914.

Application filed January 14, 1913. Serial No. 742,075.

To all whom it may concern:

Be it known that I, JACOB J. KLEIN, a citizen of the United States, residing at Kearney, in the county of Buffalo and State 5 of Nebraska, have invented certain new and useful Improvements in Closets, of which the following is a specification.

This invention relates to closets and while the principles of the invention may be embodied in closets of various types, a dry 10 closet is here shown.

It is one aim of the invention to provide, in a closet, means for feeding a perforated sheet across the seat opening so that clean 15 and sanitary portions of the sheet will be successively brought into position above the seat and incidentally the invention contemplates providing at one side of the seat, a storage compartment for the roll of paper 20 and at the other side of the seat a receiving compartment into which the used portion of the sheet is fed.

Another aim of the invention is to provide in a structure such as above briefly described, means for automatically feeding the paper across the seat as the cover for the seat is moved to open position.

The invention also contemplates the provision of means for automatically returning 30 the cover to closed position as the person using the closet arises from the seat.

In connection with the closet there is employed a disinfectant reservoir so arranged 35 as to discharge into the hopper of the closet and the invention contemplates the provision of means for automatically feeding disinfectant from the hopper as the seat is moved from one to the other of its positions.

40 In the accompanying drawings: Figure 1 is a perspective view of the closet embodying the present invention; Fig. 2 is a vertical transverse sectional view therethrough; the cover being shown in closed position; Fig. 3 is a vertical sectional view taken in a plane from front to rear; Fig. 4 is a vertical front to rear sectional view on the line 4-4 of Fig. 2; Fig. 5 is a perspective view 45 of the cover and its associated parts; Fig. 6 is a detail sectional view of a portion of the seat; Fig. 7 is a similar view illustrating the manner in which the seat section shown in Fig. 6 is mounted; Fig. 8 is a plan view 50 of a portion of the perforated paper strip fed across the seat of the closet.

Corresponding and like parts are referred to in the following description and indicated in all the views of the accompanying drawings by the same reference characters.

As above stated, a storage compartment is 60 arranged at one side of the seat and hopper of the closet and a receiving compartment is arranged at the opposite side thereof and the first of these compartments is indicated in general by the reference character 65 A and the second by the reference character B. Both compartments are preferably of box-like form and are supported upon legs 1 and the compartment A includes side walls 2 and 3, the wall 2 being presented toward the compartment B and the wall 3 being provided with a door opening and a door 4 which when opened permits of the introduction into the compartment of a roll of the perforated paper which is to be drawn 75 or fed over the closet seat. The roll is indicated at 5 and is wound upon a roller 6 fitted at one end in a bearing 7 in the forward end wall of the compartment and seated at its other end in an open bearing 8 arranged upon the rear wall of the compartment. The roller 6 carries a ratchet 9 engaged by a pawl 10 which is designed to prevent backward rotation. The compartments A and B have a common top indicated at 11 and this top serves not only to close the upper ends of the compartments but also to properly space the same and at its portion which extends between the compartments, is formed with an opening 12 cut in from its forward side and arranged to expose the closet seat when the cover of the closet is in open position. A false top 13 is arranged beneath the top 11 in the manner shown in Fig. 2 of the drawings and is 95 formed with an opening 14 corresponding in contour to the opening 12. The false top 13 projects at its ends into the two compartments A and B and as shown in said figure is spaced a slight distance below the top 11 so that the paper drawn from the roll 5 may pass between the said tops 11 and 13.

As illustrated in Fig. 8 of the drawings the paper comprising the roll 5 is formed at intervals in its length with openings 15 and as will be presently made clear, these openings are designed to register with the opening in the closet seat as successive portions of the length of the roll are drawn over the seat.

The receiving compartment B into which the paper is deposited after being used, has one of its side walls indicated by the numeral 16 presented toward the wall 2 of the compartment A and its other side wall provided with a door opening 17 normally closed by a door 18 which, however, may be opened to permit of the removal of the accumulated soiled paper deposited within the compartment.

Journaled for rotation within the compartment B, in bearings upon the forward and rear end walls thereof, is a roller 19, a similar roller 20 being journaled above the roller 19 and having its surface in contact therewith. The roller 19 carries pinions 21 and gears 22, a set of these pinions and gears being located adjacent each end of the roller. The roller 20 carries pinions 23 which mesh with the pinions 21 upon the roller 19 so that the rollers rotate in unison when rotative movement is imparted to the gears 22.

The cover of the closet is indicated by the numeral 24 and is slidably mounted upon the upper surface of the top 11 as shown in Fig. 2 and this cover is provided with spaced laterally projecting racks 25 which mesh with the gears 22 at the ends of the roller 19. A handle 26 is provided upon the cover 24 and when this handle is grasped and the cover is slid to the right in Fig. 2 of the drawings, the racks 25 riding over the gears 22 will serve to rotate these gears and impart corresponding movement to the roller 19. The gears 22 are not fixed upon the roller 19 but are clutched with this roller when rotated in one direction, by a pawl and ratchet device indicated in general at 27, they being free to rotate in an opposite direction upon the roller so that upon return movement of the rack bars 25, backward rotative movement will not be imparted to the rollers 19 and 20.

It will be apparent by referring to Fig. 2 that the sheet fed from the roll 5 is passed between the rollers 19 and 20 and is drawn by the rotation of these rollers, between the top sections 11 and 13 and deposited in the receiving compartment B.

A shelf 28 is supported beneath the top section 13 and extends between the adjacent side walls 2 and 16 of the compartments A and B and is formed with an opening 29 located beneath the openings 12 and 14. An annular plate 30 is secured upon the upper surface of the shelf 28 and surrounds the opening 29 therein and this plate is formed at intervals with upstanding lugs 31 upon which are fitted the lower ends of springs 32. The upper ends of these springs fit over lugs 33 formed at intervals in an annular plate 34 which is in this manner yieldably supported for vertical movement above the plate 30. An annular rim 35, of wood or

other suitable material, is secured upon the upper side of the plate 34 and constitutes the seat proper.

It will be apparent by reference to Figs. 2 and 3 that paper from the roll 5 is drawn above the rim 35 and that the openings in this sheet are arranged to register successively with the opening in said rim. The object in view in yieldably supporting the upper section of the seat will presently be made apparent.

Connected to the cover 24 is a cable or other flexible element 36 which is trained over a pulley 37 arranged at the adjacent end of the top 11 and a weight 38 is connected to the end of this cable and acts to return the cover 24 to closed position after it has been moved to open position and released.

It is of course expedient that some means be provided for holding the cover 24 in open position during the time the closet is in use and for this purpose two pawls 39 are mounted within recesses 40 in the underside of the cover 24 and are arranged, when the cover is in open position, to engage against stops 41 upon the upper face of the top 11. The pawls 39 are mounted upon a rod 42 which is arranged to rock and which has its ends bent to project laterally and downwardly as at 43. For a purpose to be presently explained the cover is formed at its front and rear edges and adjacent that end from which the rack bars project, with notches 44. At this point it will be clear that after the cover has been slid to the right in Fig. 2 until the pawls 39 engage with the respective stops 41, it will be held against return movement to closed position but it is of course necessary to provide some means whereby the pawls may be disengaged from the stops and the cover released when a person arises from the seat. This means is embodied in a member supported for rocking movement upon the top 11 and this member is preferably formed from a suitable length of rod or bar of metal bent to form spaced arms 45 and a connecting portion 46. Pivot pins 47 are passed through the arms 45 at points between their ends and are secured in the top 11 so that the member as a whole is supported for rocking movement. The connecting portion 46 of the member extends beneath the adjacent side of the upper or yieldably supported section of the seat and is fitted pivotally through eye members 48 secured upon the underside of the plate 34. The free ends of the arms 45 are bent toward each other as at 50 and downwardly at right angles as at 51 and thence as at 52, toward each other and parallel to their portions 50, and it is preferable that the portions 52 seat in recesses 53 in the upper side of the top 11.

It will be apparent from an inspection of 130

Fig. 1 of the drawings that when the cover is moved to open position the ends 43 of the rod 42 carrying the pawls 39 will assume a position above the end portions 50 of the arms 45 and that the notches 44 will then be located laterally beyond the portions or fingers 52 of the said arms. The parts being in this position, a person using the closet and imposing his weight upon the upper section thereof, will depress the section, thereby swinging down the connecting portion 46 of the member just described. Upon such movement of the members the fingers or end portions 50 of the arms 45 will be moved upwardly and will press forwardly against the ends 43 of the rod 42 thereby disengaging the pawls from the stops 41. This releases the cover which then moves toward the occupant of the seat until the fingers 52 engage in the notches 44, whereupon the seat will be held stationary and against closing movement. As soon, however, as the user of the closet arises from the seat, the upward or return movement of the yieldably supported section of the seat will result in corresponding movement of the inner ends of the arms 45 and in a downward swinging movement of their outer ends so that the fingers 52 will be disengaged from the notches 44, whereupon the weight 38 will act to automatically move the cover to closed position.

The hopper of the closet is indicated by the numeral 54 and is illustrated as supported upon the floor or other foundation upon which the closet is built or arranged and this hopper is provided near its front with a partition 54^a which is inclined downwardly and forwardly and which at its lower end is located relatively close to the forward side of the said hopper. A pipe 54^b is fitted in the bottom of the hopper between the forward side thereof and the partition 54^a and is arranged to discharge at any convenient point. The fact will be appreciated by reference to Fig. 3 of the drawings that the partition 54^a serves to divide the hopper into front and rear compartments and by reason of the relative location of these compartments, the user of the closet may use the forward one as a urinal whereas the rear one is designed to receive the excrement.

As before stated, means is provided for feeding disinfectant to the hopper and the reservoir for this disinfectant is indicated by the numeral 55 and is mounted upon the cover 24 in the manner clearly shown in Fig. 3 of the drawings, the cover being provided with an opening 24^a receiving the discharge spout 55^a leading from the bottom of the hopper, which bottom is inclined from all sides as shown in said figure. At its top the hopper is provided with an opening through which the disinfectant may be introduced

and this opening is normally closed by a cover 55^b. A shaft 56 is journaled for rotation in the upper end of the discharge spout 55^a and carries a spiral stirrer blade 57 which, upon rotation of the shaft, serves to loosen the disinfectant and feed the same downwardly through the spout. Loosely mounted upon the rear end of the shaft 56 is a pinion 58 meshing with a rack 59 upon the upper side of the top 11. Fixed upon the shaft is a ratchet 60 engaged by a pawl 61 upon the pinion 58, means being thus provided for clutching the pinion for rotation with the shaft in one direction but permitting of its backward rotation without affecting the shaft. The rack 59 is clearly shown in Fig. 9 of the drawings and is provided with teeth for only a relatively short portion of its length so that the shaft 56 will be rotated when the cover 24 practically reaches its closed position. It is preferable that the cover 24 be supported for travel by means of rollers and these rollers are indicated in the drawings by the numeral 62 and travel in grooves 63 in the upper side of the top 11.

Having thus described the invention, what is claimed as new is:

1. In a closet, a seat, a paper storage holder at one side of the seat, a cover mounted for sliding movement above the seat, and means actuated by a movement of the cover from one position to another for feeding paper from the storage holder, across the seat.

2. In a closet, a seat, a paper storage holder at one side of the seat, a cover mounted for sliding movement above the seat, a paper receptacle at the opposite side of the seat, and means actuated by the movement of the cover from one position to another for feeding paper from the storage holder across the seat and into the receptacle.

3. In a closet, a seat, a paper storage compartment at one side of the seat, a paper receptacle at the other side of the seat, paper feeding mechanism at the last mentioned side of the seat arranged to be actuated to draw paper from the storage compartment across the seat and deposit the same into the receptacle, a cover mounted for sliding movement above the seat, and means actuated by the movement of the cover for actuating said paper feeding mechanism.

4. In a closet, a seat having a depressible section, a cover arranged above the seat and movable to open and closed positions, means normally acting to hold the cover in closed position, means for holding the cover in open position, and means actuated by the movement of the depressible section of the seat for rendering the cover holding means inoperative.

5. In a closet, a seat having a depressible section, a cover mounted above the seat and

movable to open and closed positions, means normally holding the cover in closed position, means arranged to hold the cover in open position, and means arranged upon the 5 depression of the said section of the seat to render the cover holding means inoperative.

6. In a closet, a seat, a cover mounted above the seat and movable to open and closed positions, means normally holding the

crossed position, means normally holding the cover in closed position, means arranged to hold the cover when moved to open position, means actuated by the depression of the said section of the seat to render the cover holding means inoperative, and means also arranged for actuation by depression of the said section of the seat to hold the cover against movement to closed position after the means for holding the cover in open position has been rendered inoperative.

20 7. In a closet, a seat, a cover mounted for sliding movement above the seat, means normally tending to slide the cover to closed position, means arranged to hold the cover in open position, and means acting upon the 25 imposition of weight upon the seat, to render inoperative the means for holding the cover in open position.

8. In a closet, a seat, a cover mounted for sliding movement above the seat, means normally tending to slide the cover to closed position, means arranged to hold the cover in open position, and means acting upon the imposition of weight upon the seat, to render inoperative the means for holding the cover in open position and to subsequently act to hold the cover against return movement to closed position.

9. In a closet, a seat having a depressible section, a cover mounted for sliding movement above the seat, means normally holding the cover in closed position and tending to slide the same to closed position after its movement to open position, an abutment, a pawl carried by the cover and arranged to engage with the abutment whereby to hold the cover against return movement to closed

position, and means arranged upon the depression of the said section of the seat to disengage the pawl from the said abutment.

10. In a closet, a seat having a depressible section, a cover mounted for sliding movement above the seat, means normally holding the cover in closed position and tending to slide the same to closed position after its movement to open position, an abutment, a pawl carried by the cover and arranged to engage with the abutment whereby to hold the cover against return movement to closed position, means arranged upon the depression of the said section of the seat to disengage the pawl from the said abutment, and means arranged to act subsequent to the disengagement of the pawl from the abutment, to restrain the cover against return movement to closed position. 60 65 55 50

11. In a closet, a seat, a cover mounted for sliding movement above the seat, the seat having a fixed section and a compressible section, an abutment carried by the fixed section of the seat, a pawl carried by the cover and engageable with the abutment to hold the cover in open position, means normally tending to move the cover to closed position, an abutment carried by the cover, and a member mounted to rock upon the fixed section of the seat and arranged for actuation by the depression of the said compressible section of the seat, the said member having a portion arranged to disengage the pawl from the abutment upon depression of the last mentioned section of the seat and a portion arranged to subsequently engage with the abutment upon the cover whereby to restrain the cover against return movement to closed position.

In testimony whereof I affix my signature
in presence of two witnesses.
